Patented Nov. 5, 1968

212,646

PORTABLE RADIO CABINET

Melvin H. Boldt, Glenview, Ill., assignor to Zenith Radio Corporation, Chicago, Ill., a corporation of Delaware

Filed Aug. 21, 1967, Ser. No. 3,324

Term of patent 14 years

(Cl. D56—4)

FIG. 1

FIG. 2

FIG. 3

FIG. 4

FIG. 5

FIGURE 1 is a perspective view of my design for a portable radio cabinet shown in a closed position;

FIGURE 2 is a plan view thereof;

FIGURE 3 is a front elevational view of my design shown in an open position;

FIGURE 4 is a right side elevational view thereof shown with its front cover retracted into a lower storage compartment; and

FIGURE 5 is a perspective view of my design for a portable radio cabinet shown in an open position, with its front cover extended out of its storage compartment and its antenna positioned upwardly.

The back and bottom of my design are plain and unornamented and the dominant features of the design are shown by means of full lines.

I claim:

The ornamental design for a portable radio cabinet, substantially as shown and described.
